ATTORNEY

UNITED STATES PATENT OFFICE.

RAOUL J. HEBERT, OF WORCESTER, MASSACHUSETTS.

DIE-STOCK.

1,241,377.

Specification of Letters Patent. Patented Sept. 25, 1917.

Application filed April 21, 1917. Serial No. 163,733.

To all whom it may concern:

Be it known that I, RAOUL J. HEBERT, a citizen of the United States, residing at Worcester, in the county of Worcester and 5 State of Massachusetts, have invented certain new and useful Improvements in Die-Stocks, of which the following is a specification.

This invention relates to die stocks and 10 the primary object of the invention is to provide a stock for holding a die, and provided with means to guide the stock on the work, whereby a perfectly straight thread will be formed.

15 Another object of the invention is to provide adjustable work-engaging members carried by the die stock to act as guide members in advance of the die, thus assuring the proper formation of the threads on 20 the work.

25 A further object of this invention is the provision of a die stock which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of 30 my invention, in which;

Figure 1 is a side elevation partly broken 35 away.

Fig. 2 is a similar view, the stock being partly shown in section to disclose the interior.

Fig. 3 is a bottom plan view partly broken 40 away, showing the adjusting screw.

Fig. 4 is a top plan view.

Fig. 5 is a detail plan of two guide jaws constructed in accordance with a modified arrangement.

45 Fig. 6 is a detail perspective view of the same jaws.

Referring to the drawing, wherein is illustrated the preferred form of my invention, and in which like numerals of 50 reference indicate corresponding parts throughout the several views, the stock consists of the central casing in the form of a block 1 having the oppositely extending handles 2 of any desired length for the pur-

pose of rotating the stock when operating 55 the same. The casing has a relatively large circular recess 3 in which a die, of the usual construction, may be placed and which is shown by broken lines in Figs. 2 and 4 of the drawing. Extending through an opening in the side of the casing is a set screw 4, adapted to engage the side of the die within the recess 3 to hold the die in rigid position within the recess.

In the opposite side of the casing is a 65 transverse channel 6 in which a pair of jaws 6 and 7 are mounted. The jaw 6 has a triangular depression 8, while the jaw 7 has a triangular tongue 9 adapted to extend 70 into the depression 8, and the terminal of the tongue is cut out as at 10, so that the apex of the triangular depression 8 may 75 coact with the cut-out 10 to engage an article extended through the center of the die stock. Communication between the recess 3, and the channel 5 is established by an opening 11, while the bottom of the stock has a smaller opening 12, thus providing a continuous passageway from the top to the bottom of the stock casing.

80 The jaws 6 and 7 are slidably mounted in the channel 5, and are adjusted through the medium of an adjusting screw 13 engaged with screw threaded openings 14 provided in the jaws 6 and 7, and which are oppositely threaded with right and left hand threads to obtain the necessary movement when the screw is rotated. A knurled head 85 15 is carried by the end of the screw to facilitate its rotation.

90 The open ends of the channel 5 are normally closed by end plates 16 secured to the casing in any preferred manner, and the screw 13 is rotatably mounted in the plates to maintain a certain pre-determined position when rotated so that the necessary movement may be imparted to the guide jaws. These jaws are disposed considerably below the die which will be mounted in the recess 3 when the device is in operation. 95 By turning the screw, the jaws may be adjusted to engage a pipe or rod upon which the screw threads are to be formed. The contacting portions of the jaws serve to guide the stock so that the die will be held 100 in perfect longitudinal alinement with the pipe or rod thus assuring perfect threads when the die engages the pipe or rod and 105

performs the operation of cutting the threads.

In Figs. 5 and 6, I have illustrated a modified construction for the jaws, and it will be noted that they are adapted to be received in a channel of the size of the channel 5 in the casing 1. The jaw 17, and the jaw 18 are each provided with projecting guide flanges 19 and 20. The guide flange 19 of the jaw 18 being adapted to overlap the corresponding flange 19 of the jaw 17, while the flange 20 of the jaw 17 will underlie the flange 20 of the jaw 18. The jaws are provided with recesses so that these flanges may have room to move back and forth as the adjusting screw is rotated to move the jaws toward and away from each other.

Fig. 5 illustrates the square formation of the space between the flanges when the jaws are assembled, and by virtue of their superposed staggered relation, the flanges serve to guide the stock in which they are mounted, so that the die will be held to properly engage the work upon which the threads are being formed.

From the foregoing it will be observed that a very simple and durable die stock has been provided, the details of which embody the preferred form. I desire it to be understood, however, that slight changes in the minor details of construction may be made,

Copies of this patent may be obtained for five cents each, by addressing the "Commissioner of Patents, Washington, D. C."

without departing from the spirit of the invention or the scope of the claim hereunto appended.

I claim:

A die stock comprising a rectangular block having integral arms extending from diametrically opposite side edges thereof, a die seat in one face and a jaw seat extending transversely across the other parallel face from edge to edge thereof and opening through said edges, a relatively small opening connecting said seats, the side walls of said jaw seat being undercut, jaws fitting the undercut walls of said jaw seat and slidable therein across said opening, said jaws having registering oppositely threaded bores extending parallel with said undercut seat walls, an adjusting screw threaded to operate in said bores to move said jaws toward and away from each other, and plates closing the end of said jaw seat and in which said screw is mounted to rotate to adapt it to maintain a predetermined position relative to said jaws when rotated to insure their free sliding movement in said seat.

In testimony whereof I affix my signature in presence of two witnesses.

RAOUL J. HEBERT.
